UNITED STATES PATENT OFFICE.

CARL GUSTAV FRISTAD, OF MANDAN, NORTH DAKOTA.

SICKLE HOLDER.

Application filed April 1, 1925. Serial No. 19,962.

This invention relates to improvements in holders for supporting sickles, scythes, and the like, in order that they may be conveniently ground.

5 The primary object of the invention is the provision of an improved type of holder adapted to be used in connection with the grinding or sharpening of the long sickle blades of mowing, reaping, and cutting machines, whereby an operator may attach the same to the sickle at either end, for the purpose of obtaining a leverage by which the sickle may be balanced when sharpening the blades of the sickle at the ends thereof.

15 A further and important object of this invention is the provision of a novel type of sickle holder adapted to detachably fit between the knife or blade sections of a sickle at any point, and preferably being 20 of a type which a single individual may use in connection with the sharpening of the blades at the end of the sickle in order to balance the sickle to correctly hold the same and suitably grind and sharpen the blade.

25 Other objects and advantages of this invention will be apparent during the course of the following detailed description.

In the accompanying drawing, forming a part of this specification, and wherein similar reference characters designate corresponding parts throughout the several views,

Figure 1 is a plan view showing the relative attachment of the improved holder to a sickle, and the position which the same assumes with respect to a grindstone or other sharpening element when the end blades of the sickle are to be sharpened.

Figure 2 is a rear elevation of the improved holder in its connected relation with the sickle, and in its sharpening relation with respect to a grindstone or the like.

Figure 3 is a perspective view of the improved sickle holder.

45 Figure 4 is a fragmentary view through the sickle holder adjacent its connection with a sickle.

Figure 5 is a cross sectional view taken substantially on the line 5-5 of Figure 4, 50 showing more particularly the relative con-

nexion of the holder with the bar and blade portions of the sickle.

In the drawing, wherein for the purpose of illustration is shown only a preferred embodiment of this invention, the letter A may 55 generally designate a sickle of any approved construction, with which the improved holder B may be connected to permit sharpening of the sickle blades upon the machine or grindstone device C.

The sickle device A in the majority of instances will comprise a blade plate 10, outwardly of one edge from which the substantially V-shaped knives or blades 11 extend, as in well known construction, said blades 11 being beveled at one side thereof along their convergent edges. Supported upon the plate 10 at the normal under side thereof is the bar 12, which is positioned in a plane above the plane of the blades 11, and accommodation for which must be made in the holder B in order to properly hold the sickle device and yet prevent destruction of the blade edges.

The sharpening device C may of course 75 be of any approved construction, and in the preferred instance is the conventional grindstone which comprises a frame 15 having a supporting seat 17 at one end thereof, and rotatably supporting the pedal operated 80 grindstone 18 of the conventional type. It can be appreciated from the relation of parts illustrated in Figure 1 of the drawing, that it is a difficult operation to evenly and accurately grind the end blades 11 of the 85 sickle A, and especially is it difficult for a single individual to do so, since the extreme length of the sickle forms a leverage when the end blades are to be sharpened which

provides a weight that the operator cannot 90 support when the end blades at either end of the sickle are to be sharpened. It is therefore a purpose of the invention to provide the holder B, which detachably engages between any of the blades of the sickle 95 holder, and it extends to the opposite side of the grindstone from the major length of the sickle, so that the operator may grasp the holder with the one hand and the sickle with the other and balance the sickle over the 100

grindstone as a fulcrum point, to bear evenly upon the blade to be sharpened.

The improved holder B preferably comprises an elongated body portion 25, which 5 may be of wood, metal, or any preferred rigid material. At one end thereof the same is provided with a handle structure 26, comprising the U-shaped body portion 27 having a recess 28 therein adapted to receive the outer end of the body portion 25 of the holder B, and be riveted therein as by rivets 29. The structure 26 furthermore includes the reduced hand grasp 30 extending outwardly axially at the ends of the body 25.

The holder body 25 at the opposite end from the handle structure 26 is provided with a slot or a way 40 extending inwardly from the end edge 41, and parallel with the 20 axis of the body 25. This way 40 subdivides the outer end of the holder B into the shanks 42 and 43 which are very durable and strong enough to aid in the support of the sickle. The way 40 is formed of a width determined by the parallel edges 45 and 46 of the shanks 42 and 43, and the way 40 for the purposes of description may be considered as ending at an edge 47 of the body 25, which extends at right angles from the 25 edge 45 of the shank 42. At the inner end of the way or slot 40 a recess or pocket 48 is formed in the inner end of the slot 40 at a corner thereof, extending for a distance into the body 25 beyond the edge 47 and extending into the shank portion 43 beyond the slot facing edge 46 thereof. This pocket 48 therefore provides a portion 50 which extends upwardly into the body 25 beyond the edge 47 and provides a portion 55 which 30 extends into the shank 43 beyond the edge 46, and in the latter instance providing a shoulder 54 which aids in the support of the sickle as will be subsequently described.

Referring to the cooperative attachment 45 of the holder B upon the sickle A, the slot or way 40 is of sufficient width that the same may receive the sickle bar 12 and the body portion of the sickle plate 10 at its least width, between the blades or knives 11. 50 After the holder has been slipped onto the sickle between the proper blades 11, and the sickle moved to the end of the way 40 the holder is then moved laterally to accommodate the sickle bar 12 in the pocket 48, and 55 in thus moving the holder it is locked, so to speak, upon the sickle bar, and the sickle bar 12 is accommodated in the portion 50 of the recess 48 bearing against the upper edge of said pocket 48, and the sickle bears against the shoulder 54 of the holder shank 43, as 60 is illustrated in Figures 1 and 5 of the drawing. A blade 11^a, as is illustrated in Figure 1 of the drawing, bears against the shank 42, and in this position the holder B is disposed in an obtuse angular relation with re-

spect to the sickle A, and at the short end of the sickle, and extends beyond this end of the sickle to provide a convenient leverage for balancing the sickle upon the sharpening element 18.

From the foregoing description of this invention it is apparent that a novel type of holder for sickles has been provided, which may be detachably associated in a convenient manner at either end of the sickle, to provide 70 an extension for the sickle, by which the same may be balanced during sharpening of the end blades or knives, so that the said blades may be evenly sharpened and ground.

Various changes in the shape, size, and arrangement of parts may be made to the form of invention herein shown and described, without departing from the spirit of this invention or the scope of the claims.

I claim:

1. In a holder of the class described a body portion having a way extending inwardly from an end thereof to subdivide said end into a pair of shanks at opposite sides of the way, said body portion having a reduced recess contiguous with the way extending upwardly into the body portion beyond the inner edge of the way and also laterally into one of said shanks to provide a shoulder on said shank facing said recess.

2. As an article of manufacture a sickle holder comprising a rigid flat elongated body portion having a way formed inwardly of an end edge subdividing said handle into a pair of sickle engaging shanks, said way at the inner end thereof having a laterally extending recess communicating therewith and extending into one of said shanks to provide a shoulder facing in a direction opposite to the outlet of the way.

3. As an article of manufacture a sickle holder comprising a rigid elongated body portion having a way formed inwardly of an end edge subdividing said handle into a pair of sickle engaging shanks, said way at the inner end thereof having a laterally extending recess communicating therewith and extending into one of said shanks to provide a shoulder facing in a direction opposite to the outlet of the way, said way also extending upwardly into the body portion beyond the end edge of said way.

4. As an article of manufacture a sickle holder comprising a rigid elongated body portion having a way formed inwardly of an end edge subdividing said handle into a pair of sickle engaging shanks, said way at the inner end thereof having a laterally extending recess communicating therewith and extending into one of said shanks to provide a shoulder facing in a direction opposite to the outlet of the way, said way also extending upwardly into the body portion beyond the end edge of said way, and a hand grasping construction formed on said body

portion at the end thereof opposite said way.

5. In a sickle holder the combination of a flat piece of material having a recess extending inwardly from one end thereof to provide a pair of spaced shanks lying in the same plane, one of said shanks at the free end thereof providing an extension project-

ing into the recess, said extension in length being less than the length of the shank upon which it is placed to provide a shoulder facing towards the inner end of the recess, said extension lying in the same plane as the shanks. 10

CARL GUSTAV FRISTAD.
